[57] **CLAIM**

The ornamental design for handle for a labelling apparatus, as shown.

DESCRIPTION

FIG. 1 is a side elevational view of the handle for a labelling apparatus embodying my new design;

FIG. 2 is a top plan view of the handle for a labelling apparatus embodying my new design;

FIG. 3 is an end elevational view taken from the left hand side of FIG. 1;

FIG. 4 is a perspective view of the handle for a labelling apparatus embodying my new design, with the labelling apparatus being illustrated in broken lines and illustrative only of the environment of my design;

FIG. 5 is a bottom plan view thereof; and

FIG. 6 is an end elevational view taken from the right hand side of FIG. 1.

FIG. 5

FIG. 6
